CENTRIFUGAL BUCKET

Robert J. Birkenhauer, Richmond, Va., assignor
to E. I. du Pont de Nemours & Company, Wil-
mington, Del., a corporation of Delaware

Application November 23, 1945, Serial No. 630,498

7 Claims. (Cl. 57—76)

1

This invention relates to centrifugal buckets. More particularly, it relates to centrifugal spinning buckets employed in the bucket process of producing synthetic yarn.

One of the common methods of preparing viscose rayon yarn, i. e. regenerated cellulose yarn produced from viscose, is known as the bucket process. According to such process, a solution of viscose is extruded through a suitable nozzle or spinneret into a coagulating and regenerating bath from which the filaments of regenerated cellulose are withdrawn by a feed wheel and fed by an appropriate traversing guide into the interior of a bucket rotating at high speed. The centrifugal force created by the rotation of the bucket draws the yarn from the traversing guide and throws it against the wall of the bucket or against the layers of yarn previously laid down. The traversing guide is reciprocated axially of the bucket between the top and bottom thereof so that the yarn, as it is laid against the wall of the bucket, forms a helix.

After a cake of suitable size is formed, it is doffed and the yarn is processed either in cake form as spun or after re-winding into skeins. The processing of the yarn involves treatment with various liquids in order to remove the acid acid and soluble salts contained therein and to desulfur, bleach, dye or otherwise treat to impart desirable characteristics to the finished product. The finished yarn, irrespective of the form in which it is processed, is wound into the final textile packages, such as cones, in which form they are supplied to the textile industry.

The inner peripheral wall of one of the most commonly used types of bucket tapers about 3° upwardly from the bottom to the top of the bucket. During the formation of the cake, the cake undergoes endwise shrinkage and pulls away from both the bottom of the bucket and the bucket lid. Consequently, during the formation of the cake, the yarn will be thrown by the centrifugal force over the top and bottom of the cake to form loose threads on the outer periphery of the cake. Such loose threads are known in the art as "ears," and interfere with the unwinding of the yarn from the cake. In some instances, particularly when the yarn is formed into the final textile package from processed cakes, the ears cause breaks and plucks. Frequently, the change in tension on the yarn, during the formation of the final textile package, caused by the ears results in yarn which produces shiners in fabric made therefrom.

The results obtained because of the ears can be avoided if the ears are stripped from the cake. This requires unwinding of the yarn until the ears are removed and discarding of such unwound yarn as waste.

An object of this invention is to provide a new and improved centrifugal bucket.

Another object of this invention is to provide

2

a spinning bucket which will produce a yarn cake of improved formation.

A further object of this invention is to provide a centrifugal bucket of a construction wherein the vertical component of the centrifugal force produced by the rotation of the bucket opposes the tendency of the cake to shrink endwise.

An additional object of this invention is to provide a centrifugal bucket wherein the vertical component of the centrifugal force produced during the rotation of the bucket will be both upward from the center of the bucket.

Other and additional objects will become apparent hereinafter.

15 The above objects are accomplished, in general, by a new construction of a centrifugal bucket in which the inner wall thereof on which the yarn is laid is tapered in opposite directions to a point substantially midway between the top and bottom of the bucket, whereby, during the 20 formation of the yarn cake, the vertical component of the centrifugal force from such central point is in opposite directions (upward and downward) and opposes the shrinkage forces in the 25 yarn of the cake tending to shrink the cake endwise, i. e. pull away from the lid and bottom of the bucket, and thereby prevent the formation of ears.

The present invention will be more clearly understood by reference to the detailed description 30 when taken in connection with the accompanying drawings, wherein:

Figure 1 is a vertical section of one embodiment of a bucket of the instant invention, including also a portion of the cooperating traversing guide;

Figure 2 is another embodiment of the bucket constituting this invention; and

Figure 3 is still another embodiment of this invention.

40 Referring now to the drawings wherein like reference numerals designate like parts, and particularly to Figure 1, the reference numeral 10 designates a bucket in which the side wall 12 is formed integrally with the bottom 14 and is normally open at the top. The bottom 14 is provided with an integral hub 16 whereby the bucket may be positioned on a rotating spindle of a spinning machine. The bucket is provided with a lid 18 which is seated on an annular shoulder and is held in position by a spring clip 20. The lid 18 is provided with a circular hole 22 in the center thereof, through which a traversing guide 24 passes. The traversing guide 24 is reciprocated by a traversing bar (not shown) so that it will travel axially of the bucket from the top to the bottom thereof whereby the yarn will be drawn by the centrifugal force from the traversing guide and laid down on the inner peripheral wall of the bucket or windings previously laid down thereon in a helix to form the yarn package.

60 As is shown in Figure 1, the inner peripheral

wall of the bucket is tapered from the central point 26 in both directions to form two oppositely disposed frusto-conical surfaces 28 and 30. In the form shown in Figure 1, the frusto-conical surface 28 has a taper of 1° in the downward direction, and the frusto-conical portion 30 has a taper of 1° in the upward direction. Adjacent the bottom, the bucket is provided with drain holes 32 to permit draining of any liquids carried by or supplied to the yarn.

The invention is not restricted to the previously described embodiment wherein the double taper of the inner peripheral wall of the bucket is formed of two frusto-conical surfaces. The inner peripheral wall of the bucket, as shown in Figure 2, can comprise a smooth inwardly curved surface 40, or two smooth outwardly curved surfaces 42 and 44, as shown in Figure 3. The peripheral wall 40 is tangent to a vertical line at a point midway between the top and bottom of the bucket. The bottom of the curved section 42 and the top of the curved section 44 unite at a point which is midway between the top and bottom of the bucket.

Though, as previously described, the taper of the wall in opposite directions from the center thereof is 1°, the invention is not restricted thereto. The taper of the wall in opposite directions from the center thereof can be as much as 3° or more, depending on the amount of shrinkage that takes place in the inside of the cake, or as little as ½°. In order that the vertical component of the centrifugal force be the same, it is preferred that the taper in the opposite direction be of the same angular magnitude.

The bucket can be used in the bucket spinning process for the manufacture of synthetic yarn from viscose, cuprammonium cellulose, cellulose acetate, etc. It can also be used for the processing of yarn cakes produced therein or in similar buckets.

In operation, the bucket is positioned on a spindle which is rotated at a high speed. The yarn, after leaving the feed wheel which withdraws the filaments from the bath in which a viscose solution is extruded, passes to the reciprocating traversing guide from which it is drawn by the centrifugal force and laid down in the form of a helix on the inner wall of the bucket. This operation is continued until an annular cake of desired size is obtained. When 150-denier-60-filament viscose rayon high tenacity yarn spun by the hot dip process was collected in a bucket of the construction such as shown in Figure 1, with the traverse being 53 strokes per minute, there was produced after 5 hours an annular cake free of ears and of acceptable cake formation. When a standard 3° taper bucket was used under identical conditions, there was produced a cake having very bad ears.

It is to be noted that the cakes can be doffed from buckets of the type herein described because, after a bucket has been stopped, the bottom of the cake actually has a diameter smaller than the restricted region at the center of the bucket.

The buckets are made of materials which are corrosion-resistant and normally inert with respect to the fluids contained by the yarn after it leaves the spinning bath and also to the fluids employed when the cake is processed in the bucket. In general, satisfactory results are obtained when the bucket is made of materials such as rubber, resinous condensation products, and the like.

The invention provides a centrifugal bucket

which produces a bucket cake of acceptable formation and substantially free of ears whereby the yarn can be readily unwound either into skeins or final textile packages without waste, plucks or production of yarns which produce shiners in fabrics made therefrom.

Since it is obvious that many changes and modifications can be made in the above-described details without departing from the nature and spirit of the invention, it is to be understood that the invention is not to be limited thereto except as set forth in the appended claims.

I claim:

1. A centrifugal bucket having its inner wall tapered in opposite directions with the smaller diameter of each tapered portion uniting at substantially midway between the top and bottom of said bucket.

2. A centrifugal bucket having its inner wall tapered from about ½° to about 3° in opposite directions with the smaller diameter of each tapered portion uniting at substantially midway between the top and bottom of said bucket.

3. A centrifugal bucket having its inner wall tapered about 1° in opposite directions with the smaller diameter of each tapered portion uniting at substantially midway between the top and bottom of said bucket.

4. A centrifugal bucket having its inner wall tapered in opposite directions with the smaller diameter of each tapered portion uniting at substantially midway between the top and bottom of said bucket, the said inner wall comprising two frusto-conical surfaces uniting at their smaller diameters substantially midway between the top and the bottom of said bucket.

5. A centrifugal bucket having its inner wall tapered in opposite directions with the smaller diameter of each tapered portion uniting at substantially midway between the top and the bottom of said bucket, the said inner wall comprising a smooth inwardly curved surface which is tangent to a vertical line at a point substantially midway between the top and bottom of said bucket.

6. A centrifugal bucket having its inner wall tapered in opposite directions with the smaller diameter of each tapered portion uniting at substantially midway between the top and bottom of said bucket, the said inner wall comprising two outwardly curved surfaces, the top of one surface and the bottom of the other surface uniting substantially midway between the top and bottom of said bucket.

7. A centrifugal bucket having inside diameters shorter toward the center than toward the bottom and toward the top and the inner surfaces of its side walls tapered in opposite directions with the smallest diameter of each tapered portion uniting at substantially midway between the top and bottom of said bucket.
